COMBINED LAZY SUSAN AND CHAFING DISH

John F. Bonistall, Zanesville, Ohio, assignor to Shawnee
Pottery Company, Zanesville, Ohio, a corporation of Ohio

Application March 1, 1955, Serial No. 34,808

Term of patent 14 years

(Cl. D44—10)

FIG. 1

FIG. 3

Fig. 1 is a perspective view of a combined lazy susan and chafing dish illustrating my novel design;
Fig. 2 is a top plan view thereof; and
Fig. 3 is a side elevation thereof, partly in section.
What I claim is:
The ornamental design for a combined lazy susan and chafing dish, as shown.
